UNITED STATES PATENT OFFICE.

SAMUEL S. UTTER, OF BROOKLYN, NEW YORK.

DESIGN FOR A COOKING-RANGE.

Specification forming part of Design No. 6,745, dated July 1, 1873; application filed June 7, 1873.

To all whom it may concern:

Be it known that I, SAMUEL S. UTTER, of Brooklyn, Kings county, State of New York, have invented a new and original Design for a Range, which I call the "Stag's - Head" range, of which the following is the specification:

The accompanying photograph fully illustrates my invention.

This invention relates to new features in the design for a range; and, principally, to the ornament of a stag's head, arranged on the doors or panels of the range, and, in connection therewith, of the name "Stag's Head."

In the ornament at the top of the front of the range is an oval - shaped space, from the center of which the stag's head projects, as shown in the photograph. The oven-doors of the range have each, also, a central oval space, from which the stag's head projects, and around this oval space are rays radiating therefrom, which are inclosed by a beaded oval border.

Around this again is a plain larger oval border, and in the corners of the doors are ornaments, as shown. The smaller doors and the panels are ornamented with rays radiating from a center, and inclosed in beaded and other borders, all in keeping with the design of the larger doors. In the center of some of the panels are the letters S H in monogrammatic arrangement, as shown. On the feeder-drop are the words "Stag's Head" inclosed in a plain molded border.

What I claim is—

1. The design for a range, described and shown in the photograph, having ornaments of stag's heads.

2. As a new design, the ornament of a stag's head, used on panels or doors of a stove or range, as shown.

SAM. S. UTTER.
